UNITED STATES PATENT OFFICE.

OLE PETTER FROVARP, OF ADAMS, NORTH DAKOTA.

FLYING-MACHINE.

1,372,498.

Specification of Letters Patent. Patented Mar. 22, 1921.

Application filed September 20, 1918. Serial No. 254,965.

To all whom it may concern:

Be it known that I, OLE P. FROVARP, a citizen of the United States, and resident of Adams, in the county of Walsh and State of North Dakota, have invented certain new and useful Improvements in Flying-Machines, of which the following is a specification.

This invention relates to flying machines, and an object of the invention is to provide, in a flying machine an arrangement of propellers which will materially increase the ascensional efforts of the flying machine, enabling the same to rise in a more perpendicular manner.

A further object of this invention is to provide, in a helicopter propeller, upper and lower sections, each comprising a plurality of blades radiating from a common center, the pitch of which blades may be varied to increase the camber of the propeller blades and consequently increase their resistance to the air for augmenting their ascensional efforts and also to arrange the said blades whereby they may be operated, to present relatively concave parachute structures to retard the descent of the flying machine.

Other objects of the invention will appear in the following detailed description, taken in connection with the accompanying drawings, forming a part of this specification, and in which drawings,

Figure 1 is a side elevation of the improved flying machine.

Fig. 2 is a side elevation, on an enlarged scale of one of the helicopter propellers.

Fig. 3 is a detailed view of a superposed pair of the propeller blades of one of the helicopter propellers.

Fig. 4 is a detail section on the line 6—6 of Fig. 2.

Referring more particularly to the drawings, 1 indicates the fuselage of the flying machine which is preferably boat shaped, rendering the flying machine adaptable for travel over water as well as through the air.

Cowls 17 are carried beneath the upper aerofoil 4 and guide streams of air from the tractor propellers to the helicopter propellers generically indicated by the numeral 20, one of which is positioned behind each pair of tractor propellers.

The helicopter propellers are identical in

construction and each of them include a vertical operating shaft 21 which may be connected, in any suitable manner, such as by beveled gears indicated at 22 to an operating shaft 23, which latter shaft may be connected to any suitable type of motor or engine for rotating the shaft 21 and consequently rotating the helicopter propellers.

The helicopter propellers each include upper and lower propeller members 24 and 25 and these members include a plurality of blades 26 which radiate from a common center, namely the axis of the vertical operating shaft 21. The blades 26 may be constructed of any suitable material and they are reinforced along certain of their edges by reinforcing strips 27. The blades 26 of the upper propeller 24 are connected to the blades 26 of the lower propeller by struts 28, so that the blades of these propeller sections will move in unison. The propeller blades 26 are connected to the shaft 21 in any suitable manner, and each of the blades 26 of the lower propeller section has a rod 27 connected thereto which rod extends downwardly and is connected to the flanges 28 and 29 of a slidable collar 30. The collar 30 is slidably mounted upon the shaft 21 and has an operating arm 31 connected thereto for shifting the collar. When the collar 30 is moved upwardly upon the shaft 21, the propeller blades 26 will be warped as indicated in Fig. 3 of the drawings to vary the transverse angle or pitch of the blades and increase their air striking surfaces, consequently increasing the agitation of the air and augmenting the ascensional efforts of the flying machine. Through the connecting members 28, the propellers 26 of the upper propeller section 24 will be warped in unison with the warping of the propeller blades 26 of the lower section.

A ring 32 is supported, by suitable brace members 33 which are in turn formed upon and attached to a collar 34 that is swaged upon the shaft 21 or otherwise suitably connected to the shaft for rotation therewith. Braces 35 rise from the ring 32 and brace the propeller blades 26 of the lower propeller section 25, at the edges of these blades remote from the edges or corners to which the operating rods 27 are connected, holding these edges or corners stationary during the

upward or downward movement of the corners to which the operating rods are connected, which results in the proper warping of the propeller blades.

- 5 During the rising of the flying machine, the propeller blades 26 are warped, which augments the action of the helicopter propellers and enables the flying machine to rise in a substantially perpendicular path or at
- 10 any rate in a more perpendicular path than could be followed by airplanes employing the ordinary tractor or pusher propellers without embodying in connection therewith helicopter propellers.
- 15 When the propeller blades 26 are in their normal position, or in an un-warped condition, they form substantially concave parachute sections which during the rotation thereof will assist in retarding the descent
- 20 of the flying machine enabling it to fall or descend gradually or in case of accident, such as the breaking down of the motor which operates the tractor propellers or numerous other accidents, the machine will
- 25 be prevented from disastrous descent by the co-action of the helicopter propellers when the blades thereof were in their un-warped position, with the remainder of the wing surface of the airplane.
- 30 Changes in details may be made without departing from the spirit of this invention, but;

I claim:

1. In a flying machine structure, a helicopter propeller comprising upper and lower propeller sections, each of said sections comprising a plurality of propeller blades radiating from a common center and normally having all of their edges in the same plane
- 35 and in close proximity to each other forming hollow cones with their concave surfaces downwardly, and means for warping said propeller blades to vary the pitch thereof to increase the air engaging surface of the
- 40 blades.
- 45 2. In a flying machine structure, a helicopter propeller comprising upper and lower

propeller sections, each of said sections comprising a plurality of propeller blades radiating from a common center and normally 50 having all of their edges in the same plane and in close proximity to each other forming hollow cones with their concave surfaces downwardly, and means for warping said propeller blades to vary the pitch thereof to 55 increase the air engaging surface of the blades, and means connecting the corresponding blades of said upper and lower sections for warping them in unison.

3. In a flying machine structure, a helicopter propeller comprising a central vertical standard, a plurality of blades radiating from the longitudinal axis of said standards, and arranged in upper and lower sets, the edges of said blades in each set normally 60 lying in the same plane, a reinforcing ring supported from said standards beneath the lowermost set of blades, supports carried by said ring and engaging and connecting corresponding corners of said blade, and 65 means slidably carried by said standards and connected to the edges of said blades other than those connected to said rings for warping the blades to move the edges which are 70 free from connection with said reinforcing 75 ring out of the plane of the remaining edges to vary the pitch of the blade.

4. In a flying machine structure, a helicopter propeller comprising a central vertical standard, a plurality of blades radiating 80 from the longitudinal axis of said standards, a reinforcing ring supported beneath said blade and by said standards, supports carried by said rings and engaging corresponding outer edge corners of said blade for 85 maintaining the adjacent edges thereto against movement, means slidably carried by said standards, means connecting said last named means to the edges of said blades remote from those which are connected to said 90 ring for warping the blades upon sliding movement of said slideable means to vary the pitch of the blades.

OLE PETTER FROVARP.
